UNITED STATES PATENT OFFICE.

CHARLES O. HASKELL, OF LOS ANGELES, CALIFORNIA, ASSIGNOR, BY MESNE ASSIGNMENTS, TO CENTRIFUGAL MACHINERY COMPANY, OF LOS ANGELES, CALIFORNIA, A CORPORATION OF CALIFORNIA.

AMALGAMATOR.

1,148,770.

Specification of Letters Patent.

Patented Aug. 3, 1915.

Application filed July 3, 1912, Serial No. 707,515. Renewed January 11, 1915. Serial No. 1,715.

To all whom it may concern:

Be it known that I, CHARLES O. HASKELL, a citizen of the United States, residing at Los Angeles, in the county of Los Angeles, State of California, have invented new and useful Improvements in Amalgamators for Use in Extracting Gold from Gold-Bearing Material, of which the following is a specification.

- 10 My invention relates to an improved apparatus for amalgamating and separating gold, or other metal, from the ore. Heretofore it has been customary to depend upon gravity to cause the particles of gold to settle into the mercury. This is unsatisfactory in many instances due to the fact that the gold bearing material as it comes from the stamp mill is often in a slimy condition, due to excessive hammering in the mill, and 20 floats on top of the ore. Furthermore, if the gold is coated with oil it also tends to float on a liquid vehicle carrying the ore.

The object of my invention is to obviate these difficulties and for that purpose I have 25 devised a centrifugal machine provided with a plurality of amalgam chambers in the path of the ore bearing vehicle, the operation of which causes the gold to be positively forced into contact with the mercury, thus insuring complete amalgamation.

It is also an object to provide what I term an expansion dome which prevents any of the mercury from passing off in a slug.

I accomplish this object by means of the 35 apparatus described herein and shown in the accompanying drawings, in which:

Figure 1 is a central vertical section of my device. Fig. 2 is a detail section showing the mercury as spread over the vertical 40 wall in the mercury chamber parallel with the peripheral edge of the flange by the centrifugal action of the amalgamator.

Referring now to the drawings in detail, 1 represents a base on which are supported 45 the columns 2, carrying at their top the cross head 3, all held together by long bolts provided with suitable securing means. The columns 2 are preferably formed of cylindrical sections of various lengths, between 50 which are interposed the various frames carrying the bearings for the revolving member.

Supported centrally in the base and cross

head is the hollow shaft composed of two sections, an upper section 5 with a bearing 55 in the cross head and a lower section 6, seated in the base. Between the two sections of the shaft is the amalgamator member proper, the two shaft sections serving as inlet and outlet communications for the ore 60 passing through the amalgamator. Suitable packing glands 7 surround the free ends of the shafts and are axially chambered to continue the passages formed by the shaft sections, suitable threaded ends being provided 65 in these chambers to attach pipes thereto to convey the ore bearing medium, by wet or dry process. On the lower shaft section 6 is mounted the drive pulley 8, supported between the two shelves or journal supports 9 70 and 10, these latter being supported by the sections 11 and 12 of the columns.

Ball bearings 13 are provided in each support and a thrust bearing support 14 is arranged in the support 10 to carry the weight 75 of a revolving member which constitutes the amalgamator housing and consists of the lower hemispherical bowl 15 provided with the threaded inner periphery which registers with threads cut on the outer periphery of the inverted bowl 16. Each one of these bowls 15 and 16 has a concentric threaded opening adapted to be secured to the threaded ends of the respective shaft sections 5 and 6. The shaft section 6 is extended above the floor of the bowl 15 and passes through the mercury chamber 17 therein, to support above this latter the terminal hood. The bowl 15 is formed with a rim or lip 19 adjacent its upper end which 90 engages with a corresponding lip 20 on the bowl 16 to form an annular trough 18 for containing mercury, which is adapted to be conveyed to the trough 18 from the chamber 17.

To provide for the easy travel of the mercury from the main supply in the chamber or trough 17, I provide a siphon 21, opening in the chamber 17 and through which the mercury will travel and enter the channel 100 18 by the centrifugal action set up when the housing is revolved. Suitable exit openings to withdraw the amalgam from the chambers are shown at 23 and 24.

A number of conical lugs acting as 105 spacers, preferably four, are provided in

the lower portion of the bowl 15, formed with conical recesses adapted to receive conical studs 26 formed on the lower segment 28 of the expansion or secondary amalgamation chamber. This chamber is composed of a lower apertured segment and the hemispherical expansion dome or top 29, each being provided with annular rims as 30 and 31, adapted to receive a plurality of securing devices. Mounted between the two rims 30 and 31 is an annular plate or disk 32 provided on its outer periphery with a widened edge formed by inclining the surfaces of the plate away from each other, thus forming an annular channel 33. The annular disk is so situated that its outer periphery 34 extends into the trough or chamber 18. To securely hold the two sections 28 and 29 and the disk together bolts 35 are passed through the rims 30 and 31 and the disk 32. When thus assembled a secondary amalgamation chamber is rigidly held in the primary chamber by the bolts 36 threaded in the bowl 16, the bolts 25 being locked by nuts 37. The inner ends of the bolts bear on the secondary chamber and force the studs 26 to their conically formed seats in the lugs, which also act as spacers.

38 Situated in the secondary chamber and its lower surfaces concentrically formed in relation to the inner surface of the segment 28, is a bowl 39 threaded at its apertured base to the upper end of the lower shaft section. The top of the bowl 40 acts as a deflecting flange, being provided with an aperture 41 formed with an annular lip, projecting slightly above the plane of the top surface.

42 The siphon 21 extending from the bottom of the trough 17 to the trough 18 is shown as a bent tube with a yoke 44 carried half way around the shaft 6, but grooves may be formed in the walls and inclosed to perform the same function. Holes 45 are formed in the walls of the siphon 21 through which the mercury passes and by the centrifugal action carries it up without possible interruption by the current of the ore bearing medium. Exit is through the opening 46 placed in the side of the closed end of the tube, a position away from the direction of rotation. The operation of my improved amalgamator is as follows: Mercury having been deposited in troughs 17 and 18 the device is set in rotation by connecting the pulley 8 to any suitable source of power. Ore suitably mixed with air or water is then forced by pressure into the amalgamator through the top section 5 of the shaft into the first section of the amalgamation chamber. The rotation of the device causes the mercury to spread outward in the trough 18, as clearly shown in Fig. 2, and leaves a narrower channel for the ore

to traverse. From the lower trough 17 the mercury travels upward in a thin film on the sides of the chamber where it meets the ore passing over the lip 19 and continues on through the circuitous channel formed by the other walls of the component parts of the amalgamating member. The ore is thus forcibly impinged against the mercury by the centrifugal force and intimately mixes with it and no clogging is permitted, resulting in a complete amalgamation of the metals. The ore is then carried on through the channel of general concentric form until it reaches the expansion chamber above the flange 41, where the heavier particles in the pulp are compelled to slide off and carried down and out, especially small globules of amalgam, and the material less the "values" passes into the exit opening and through the lower section of the shaft. It has been found by actual operation of the device that if the expansion dome and the deflecting flange 41 are not provided some of the mercury as amalgam will pass out of the machine in lumps or slugs.

Attention is called to the fact that the mercury pockets will retain the mercury irrespective of whether the machine is rotating or not, in other words, the pockets will retain the mercury when the centrifugal body of the machine is standing still.

What I claim is:

1. An amalgamating device, comprising a hollow revoluble drum provided with a mercury trough on its inner surface, an expansion chamber mounted within said drum and communicating at its lower end with the interior of said drum, means for rotating said drum and said expansion chamber, and means for supplying ore to the upper portion of said drum above said mercury trough.

2. A centrifugal amalgamating device, comprising a hollow revoluble body provided with mercury troughs on its inner surface, a dome mounted centrally thereof forming an upwardly expanding chamber, a discharge pipe mounted axially of said body, said discharge pipe being provided with a deflecting flange, and means for supplying ore to said body above said mercury troughs.

3. A centrifugal amalgamating device, comprising a hollow revoluble body provided with mercury troughs on its inner surface, a dome mounted centrally thereof forming an expansion chamber, means for supplying ore to said body, means for discharging the ore residue therefrom comprising a pipe mounted axially of said body and extending within said dome and provided within said dome with an upwardly deflecting flange, and means for rotating said body.

4. A centrifugal amalgamating device, comprising a hollow revoluble spherical body provided with mercury troughs on its

inner surface, a dome mounted centrally to form an expansion chamber within said body and rotating therewith, a discharge pipe mounted axially of said body, and 5 means for supplying ore to said body.

5. A centrifugal amalgamating device, comprising a hollow revoluble body provided with mercury troughs in its wall outside of but opening to its inner surface and 10 means for rotating the same, a dome mounted centrally thereof to form an expansion chamber, means for supplying ore to said body, means for discharging the ore residue therefrom comprising a pipe mounted axially of said body and extending within said dome, and means for rotating said body and said dome.

6. In a centrifugal machine of the class described, in combination, an outer shell 20 having an annular trough in the wall thereof of opening on the inner surface of said shell, an inner shell disposed within said outer shell, said inner shell being of smaller dimensions than said outer shell whereby a 25 space is formed between said shells, said inner shell having a free opening communicating with said space, means for introducing ore into said outer shell, means for rotating said shells in unison whereby the ore passes 30 into said inner shell from said outer shell, and means for withdrawing ore from said inner shell on said axis of rotation.

7. In a centrifugal machine of the class described, in combination, an outer shell having an annular mercury trough formed 35 therein and having a mercury trough at the base thereof, an inner shell forming an expansion chamber within said outer shell and having a mouth on the lower side thereof 40 projecting downward and inward toward said second named mercury trough, means for revolving the shells, and means for withdrawing the ore from the interior of said

expansion chamber and on the axis of rotation of said shells.

8. In a centrifugal machine of the class described, in combination, an outer shell having an annular trough in the wall thereof, an inner shell mounted within said outer shell, leaving a chamber between the walls of 50 said shells with which said trough communicates; said inner shell having a downwardly extending mouth disposed adjacent to the bottom of said outer shell, a discharge tube extending downwardly from the interior of 55 said inner shell through said opening and through the bottom of said outer shell, means for supplying ore to said chamber, and means for rotating said shells upon the axis of said discharge tube.

9. A centrifugal amalgamator, comprising an outer shell having an annular trough in the wall thereof, an inner shell mounted within said outer shell adapted to form a concentric space between the walls of 65 said shells, and an annular disk secured to said inner shell, and adapted to register in said annular trough, whereby a circuitous channel is formed around said walls and through 70 said trough.

10. A centrifugal amalgamator, comprising an outer shell having a plurality of annular mercury troughs on its inner surface, and conduit means to connect said troughs whereby mercury will be carried from one 75 trough to the other by centrifugal action without interruption from a reverse current of pulp carried in said shell.

In witness that I claim the foregoing I have hereunto subscribed my name this 24th 80 day of June, 1912.

CHARLES O. HASKELL.
